Patented May 9, 1922.

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

1,415,455.

Specification of Letters Patent.

Patented May 9, 1922.

Application filed June 25, 1920. Serial No. 391,675.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to the paper-feeding devices of typewriting machines, and is illustrated in connection with an Underwood typewriting machine. Certain features are disclosed in the application of William F. Helmond, Serial No. 372,481, filed April 9, 15 1920, in which front upper feed-rolls run upon the usual platen, said feed-rolls capable of being swung to and from the platen. The devices shown in said application are applied to ordinary typewriter carriages, but the 20 shaft which carries these upper feed-rolls is necessarily thin, and would yield if made of such length as to be suitable for pressing the rolls against a long platen, and the rolls would therefore fail to properly hold work- 25 sheets upon the platen.

To overcome this difficulty, the swinging support which carries the long feed-roll shaft is constructed with a stiffening rod, and a brace or braces are slidably thereon, 30 said braces also connecting with the feed-roll shaft, with the result that the shaft and the rod, taken together with their supports and braces, form a truss device. The feed-rolls are journaled upon the feed-roll shaft 35 between U arms, forming part of the brace, with the result that the brace has most effect at the point where the feed-roll bears upon the platen.

Other features and advantages will here- 40 inafter appear.

In the accompanying drawings,

Figure 1 is a plan view of a shift frame of the kind of machine described, showing the present invention as applied thereto.

45 Figure 2 is a section through an upper front feed-roll, its adjacent brace, and also showing the shafts.

Figure 3 is a sectional side view of the parts seen in Figure 1.

50 Figure 4 is a fragmentary perspective view, showing the relationship of a brace to its two shafts.

The usual Underwood platen 1 is journaled by its axle 2 in ends 3 and 4 forming 55 part of a platen shift frame, which also in-

cludes a rear paper table 5 and rear and front bottom feed-rolls 6 and 7. When it is desired to hold a work-sheet closely to the platen about the printing line, upper front feed-rolls 8, slidably journaled upon a rod 60 or shaft 9 extending along the platen 1, may be swung against the platen by pressing rearwardly upon a finger-piece 10 to swing the supports 11 of the shaft 9 rearwardly, rotating the supports with their shafts 12 and 65 13 which are journaled in extensions 15 of brackets 16 upon the frame ends 3 and 4. The brackets 16 are detachably mounted upon said ends, and, for this purpose, comprise rearward extensions 17, each having a 70 forked end 18 adapted to slip under a head 19 of a shouldered screw 20, the front end of each bracket fitting against a shouldered screw 21 at the front of the shift frame, said screws 20 and 21 being adapted to fit 75 in the screw holes for the usual cover plate screws of the ends. If the fork 18 fits very closely to the screw 20, it may be necessary to loosen the latter to insert or remove the 80 fork.

In order to detachably hold the front ends of the brackets 16 by the screws 21, each bracket 16 is provided with a catch 22 pivoted thereto at 23, and adapted to be normally pressed by its spring 24, so that its 85 edge 25 catches beneath one side of the shouldered screw 21. To enable the brackets 16 to be removed, the catches 22 are adapted to be swung against the tension of their springs 24, being for this purpose provided with 90 finger-pieces 26 and with guide-slots 27, which engage under a headed pin 28 to limit the throw when the finger-piece is actuated. The catch may be substantially identical with the catch shown in the applica- 95 tion aforesaid.

The shafts 12 and 13 are provided with enlarged hubs 29, as described in said application, by which they bear in the extensions 15, each hub being freely slidable through 100 its extension 15, as clearly set forth in said application.

In order to hold the shaft 9 to keep its feed-rolls 8 against the platen 1, there are provided cam arms 30 in which the springs 105 24 are anchored, said arms adapted to bear against outside cam extensions 31 of the shafts 12 and 13 to hold the rolls 8 down against the platen. The extensions 15 may be provided with enlarged bearings or jour- 110

nals 32 for the hubs 29, and one of these journals may be provided with a ledge 33, adapted to be engaged by a pin 34 to limit the rotation of the shafts 12 and 13 when 5 swung away from the platen.

In accordance with the present invention, in order to give sufficient stiffness to the device to enable the feed-rolls 8 to bear firmly against the platen of a long typewriter carriage, and to prevent the shaft or bar 9 from yielding in the long distance between its two supports 11 in such a machine, there is provided a stiffener comprising a second bar or stiffening rod or shaft 35 fast in the supports 11, and advantageously placed radially of the platen outside the shaft 9, in the roll-urging position of the latter. The shaft 35 may be of considerably greater diameter than the shaft 9, if desired, since it does not need to be small enough to be embraced by the feed-rolls. In order to stiffen or brace the lighter shaft 9 from the nearby stiff shaft 35, there is provided a brace member having a body 36, which engages the shaft 35 closely, but is slidable thereon, said body comprising integral extensions 37 forming a U, which are bored to slidably but closely fit the shaft 9, with the result that the radial thrust of the shaft 9, when its rolls bear 30 against the platen, is taken by the shaft 35 or largely shared by said shaft. Usually there will be a series of braces 36, and each brace may advantageously have lying between its U extension arms 37 a feed-roll 8, 35 said feed-rolls, as described in said application, comprising a rubber surface 38, confined by a head 39 on a body or barrel 40, in which is mounted a friction clasp or collar 41. The feed-rolls 8 also comprise a 40 screw 42, having a head 43 adapted to be screwed down to confine the clasp 41 within the barrel, and the peripheral part 38 on the body 40.

It has been found that the structure described forms a truss device admirably adapted to receive the strain of the feed-rolls 8 when bearing against a long platen and prevent the shaft 9 from yielding. Moreover, the brace body 36 forms a finger-piece 45 for sliding the rolls 8 along the rod. As herein shown, there are two feed-rolls 8, each having its own brace 36. Since the two rods 9 and 35 are located radially of the platen, the shaft or rod 35 has substantially no more 50 effect in obscuring the typewritten matter upon the work-sheet than the shaft 9.

It is to be noted that the stiffening rod or bar 35 extends along the full length of and is substantially coterminous with the lighter 55 journal-forming rod 9, and that the adjacent ends of these rods or bars are firmly tied together by the supports 11.

When it is not desired to use the feed-rolls 8, the finger-piece 10 is actuated as described, and the two rolls take the dotted-

line position shown in Figure 3, in which they are clear of interfering parts.

Variations may be resorted to within the scope of the invention, and portions of the improvements may be used without others. 70

Having thus described my invention, I claim:

1. In a typewriting machine, the combination with a platen and a platen frame having ends, of an upper feed-roll to run upon 75 the platen, a shaft upon which said roll is slidably journaled, supports for said shaft in said ends, a second stiffening shaft located radially of the platen in front of the first shaft, and a slidable brace engaging both of 80 said shafts and connected to slide with a roll.

2. In a typewriting machine, the combination with a platen and a platen frame having ends, of an upper feed-roll to run upon the platen, a shaft upon which said roll is slidably journaled, brackets on said ends, supports rotatable upon said brackets and carrying said shaft, a second stiffening shaft fast in said supports outside the first shaft, and a 85 slidable brace engaging both of said shafts and connected to slide with the feed-roll.

3. In a typewriting machine, the combination with a platen and a platen frame having ends, of an upper feed-roll to run upon the platen, a rod device upon which the roll 95 is slidably revoluble, a stiffener for the rod extending longitudinally thereof, brackets on said ends, and a support on each bracket for the adjacent ends of the rod and stiffener and rotatable upon its bracket to move the 100 roll to and from the platen.

4. In a front-strike typewriting machine, the combination with a traveling platen carriage, of a platen frame in said carriage, upper front feed-rolls adapted to press work-sheets against the platen above the printing line, a pair of rods for supporting said front rolls, a support at each end of the platen frame for the outer ends of both rods, and a 105 slidable brace connecting the rods and supporting the feed-roll to slide with the adjacent feed-roll along the rods. 110

5. In a front-strike typewriting machine, the combination with a traveling carriage and a platen frame, of a platen, a rod adjacent the platen forming a journal, an encircling feed-roll slidable along said rod as a journal to hold work-sheets upon the platen above the printing line, a stiffening rod adjacent the first rod, and a brace slidable upon 115 said rods and closely engaging both to stiffen the journal rod and adapted to slide the feed-roll with it.

6. In a front-strike typewriting machine, the combination with a traveling carriage 120 and a platen frame, of a platen, a rod adjacent the platen forming a journal, an encircling feed-roll slidable along said rod as a journal to hold work-sheets upon the platen above the printing line, a stiffening rod ad- 125

5 jacent the first rod, and a brace having arms embracing said feed-roll so that the sliding of the brace slides the feed-roll, said brace closely embracing both rods to stiffen the journal rod by the stiffening rod.

7. In a front-strike typewriting machine, the combination with a traveling carriage and a platen frame, of a platen, a rod adjacent the platen forming a journal, an encircling feed-roll slidable along said rod as a journal to hold work-sheets upon the platen above the printing line, a stiffening rod adjacent the first rod, a brace slidable upon said rods and closely engaging both to stiffen the journal rod and adapted to slide the feed-roll with it, and a mounting for said rods to enable them to be swung away from the platen to carry the feed-roll clear of the platen.

20 8. In a front-strike typewriting machine, the combination with a traveling carriage and a platen frame, of a platen, a rod adjacent the platen forming a journal, an encircling feed-roll slidable along said rod as a journal to hold work-sheets upon the platen above the printing line, a stiffening rod adjacent the first rod, supports tying together the adjacent ends of the rods, a brace having arms embracing said feed-roll, so that the sliding of the brace slides the feed-roll, said brace closely embracing both rods to stiffen the journal rod by the stiffening rod, and a mounting for said rods to enable them to be swung away from the platen to carry the feed-roll clear of the platen.

30 9. In a typewriting machine, the combination with a platen and a platen frame, of a stiff rod supported near the platen by said frame, a finger-piece slidable along said rod, a lighter rod nearer the platen and substantially coterminous with the first rod, supporting means tying together the adjacent ends of the rods, extensions of said finger-piece engaging the lighter rod, and a feed-roll lying between said extensions and encircling said lighter rod as its journal.

40 10. In a typewriting machine, the combination with a platen having an axle and a platen frame, of a stiff rod, a finger-piece slidable upon said stiff rod, a lighter rod lying between the stiff rod and the platen axle, so that the two rods are arranged radially of the platen, extensions of said finger-piece embracing the lighter rod, so that the lighter rod is stiffened by the stiff rod, a feed-roll lying between said extensions, and a revoluble mounting for said rods connected to said frame to enable them to be swung to and from the platen to carry

50 60 the feed-roll to or from the platen.

11. In a typewriting machine, the combination with a platen having an axle and a

frame, of a stiff rod, a finger-piece slidable upon said stiff rod, a lighter rod lying between the stiff rod and the platen axle, so that the two rods are arranged radially of the platen, extensions of said finger-piece embracing the lighter rod, so that the lighter rod is stiffened by the stiff rod, a feed-roll lying between said extensions and journaled 65 on the lighter rod, and a bracket detachably connected to said frame, said bracket comprising journals and a support for said rods journaled in said bracket, said support comprising means for tying together the adjacent ends of said rods.

70 12. In a typewriting machine, the combination with a platen and a frame having ends, of a bracket detachably connected to each end, a bearing in each bracket, a shaft 80 rotatable in each bearing, a plate fast to each shaft, a pair of rods forming a truss device connecting said plates, a feed-roll encircling one of said rods as its journal, a brace embracing both said rods to truss 85 them and having ends which lie on each side of the roll, and means normally holding said roll against the platen, but adapted to permit the plates to be rotated with the rods to carry the feed-roll away from the platen. 90

13. In a typewriting machine, the combination with a platen and a platen frame, of a stiff rod supported near the platen by said frame, a finger-piece slidable along said rod, a lighter rod nearer the platen, extensions of 95 said finger-piece engaging the lighter rod, a feed-roll lying between said extensions and encircling said lighter rod as its journal, plates upon which said rods are mounted, brackets on said frame forming supports for 100 the plates, and a spring normally turning the roll toward the platen, but adapted to let it be swung away from the platen.

14. In a typewriting machine, the combination with a revoluble platen, of a plurality 105 of bars extending along the platen, a brace member connecting together and slidably upon said bars, and a feed-roll for the platen carried by said brace member to slide therewith.

15. In a typewriting machine, the combination with a revoluble platen, of a plurality of bars extending along the platen, a brace member connecting together and slidably upon said bars, a feed-roll for the 115 platen carried by said brace member to slide therewith, and supports for the adjacent ends of the bars movable to move the feed-roll into or out of cooperative relation with the platen.
